(57) **CLAIM**

The ornamental design for a vaporizer, as shown and described.

DESCRIPTION

FIG. 1 is a front, top perspective view of a vaporizer comprised of a body and a transparent cap;

FIG. 2 is a bottom perspective view of the vaporizer including the transparent cap shown in FIG. 1;

FIG. 3 is a top perspective view of the vaporizer including the transparent cap shown in FIG. 1 in an inverted position; FIG. 4 is another top perspective view of the vaporizer including the transparent cap shown in FIG. 1 in an inverted position;

FIG. 5 is a front view of the the vaporizer including the transparent cap shown in FIG. 1 in an upright position; FIG. 6 is a first side view of the vaporizer including a transparent cap shown in FIG. 1;

FIG. 7 is a second side view of the vaporizer including the transparent cap shown in FIG. 1;

FIG. 8 is a top view of the vaporizer including the transparent cap shown in FIG. 1;

FIG. 9 is a rear view of the vaporizer including the transparent cap shown in FIG. 1;

FIG. 10 is front perspective view of the transparent cap, the cap removed for ease of illustration;

FIG. 11 is a front view of the transparent cap shown in FIG. 10;

FIG. 12 is a first side view of the transparent cap shown in FIG. 10;

FIG. 13 is a second side view of the transparent cap shown in FIG. 10;

FIG. 14 is a top view of the transparent cap shown in FIG. 10;

FIG. 15 is a bottom perspective view of the transparent cap shown in FIG. 10; and,

FIG. 16 is a bottom view of the transparent cap shown in FIG. 10.

The vaporizer including the transparent cap and the transparent cap itself are not limited to the scale shown in the drawings, and is not necessarily limited to use in the systems mentioned in the description of the illustrated subject matter. Any surface indicia shown in the drawings is merely exemplary and non-limitative.
